FOLDABLE REEL

James C. Hancock, Roanoke, Va.

Application June 21, 1946, Serial No. 678,415

1 Claim. (Cl. 242—115)

1

This invention relates in general to reels and in particular to those of the folding type which are particularly suitable for use in winding on wet fish lines and the like to dry.

The general object of the invention is to provide a foldable reel which is of simple construction and which may be manufactured easily and at low cost.

Another object is to provide a reel which may be quickly erected from its folded position and vice versa. A more specific object is to provide a reel of the class described having a plurality of arms which extend radially from a common support spindle that serves as a handle for holding it, and in which the arms may be easily and quickly moved from a nested position to predetermined spaced angular positions about the spindle axis to thereby erect the reel.

Still another object is to provide a reel of the folding type in which all of the parts are safely secured together when folded, thereby obviating all possibility of losing any of them when the reel is being carried in its collapsed condition. Still another object is to provide a reel of the class described which may be knocked-down from its erected position without removing any of the parts. Yet another object is to provide a reel that folds flat when knocked down and which may be stored in a small space.

These and other objects and advantages of the improved reel construction will become apparent from the detailed description which follows when considered with the drawings which show preferred embodiments of the invention.

In the drawings, Figs. 1-6 illustrate one form of a reel constructed in accordance with the invention, in which Fig. 1 is an isometric view showing the manner in which the reel is used when erected; Fig. 2 is also an isometric view of the same reel when erected, but drawn to a somewhat larger scale; Fig. 3 is a side elevation showing the reel when folded; and Figs. 4-6 are elevations of each of the several arms which constitute the reel.

Figs. 7-9 illustrate a modified form of the invention, in which Fig. 7 is an isometric view of the reel as erected, while Figs. 8 and 9 are fragmentary views, in plan, of the reel arms showing alternative arm constructions for the assembly shown in Fig. 7.

Referring now to Figs. 1-6, the improved reel is comprised of a spindle 10, one end of which is threaded as at 10a, while the other end 10b is finished smoothly to form a hand member by which the spindle is grasped when the reel is used,

2

as shown in Fig. 1. Spindle 10 is also provided with a collar or shoulder 10c.

A sheet metal plate 11, shaped generally in the form of an equilateral triangle is provided for spacing three radially extending reel arms 12, 13 and 14 120° apart about the spindle axis. One corner of the plate 11 is formed with ears 15, 16 that are bent over to form a closed channel; and by which the plate is securely held to arm 12 as shown in Fig. 4. Arm 12, which is preferably made from light weight rod stock such as aluminum has an eye 12a in one end which registers with the central opening 11a in the plate 11. The other two corners of plate 11 are crimped to provide open channels 17 and 18 which receive and hold the two other arms 13, 14 in spaced angular position relative to arm 12 when the reel is erected. Arms 13, 14 are likewise formed with eyes 13a, 14a, respectively, and all three of the arms together with plate 11 are adapted to be mounted adjacent each other on the threaded end portion 10a of spindle 10 as shown in Fig. 3. The shoulder portion 10c formed on the spindle acts as a stop for the eye portions of 12-14, and a wing nut 21 is provided to clamp the arms on the spindle when the latter are nested or folded as shown in Fig. 3 and also to maintain the arms in their predetermined spaced angular positions on the spindle after the reel has been erected.

As clearly shown in Fig. 3, the open channels 17, 18 formed in plate 11 face in the opposite direction from the closed channel which is formed by the bent-over ears 15, 16; thus when assembling the arms 12-14 on spindle 10, arms 13, 14 are put on first, followed by arm 12 and the plate 11 secured thereto, the plate being positioned with the open channels 17, 18 facing in the direction of arms 13 and 14.

The opposite end portions of the arms 12 and 13 are bent angularly outward of the threaded end of spindle 10 and then back upon themselves so as to provide portions 12b, 13b that lie parallel with the longitudinal axis of the spindle 10. The opposite end of arm 14 is bent angularly in a direction inwardly of the threaded end of the spindle 10 i. e. towards handle 10b, and then back upon itself so as to also provide a portion 14b parallel with the spindle axis.

It will be noted, in particular from Fig. 3, that arms 12-14 are bent in such manner that the radially extending shank portions of the arms are centrally located with respect to their axially extending end portions 12b, 13b and 14b, and that the arms are further bent back upon themselves

at both ends of the axial portions to form guides 12c-14c which prevent the line from slipping off the reel after it has been wound on. Also the outer end of one of the arms, such as arm 14 extends for a short distance parallel with the spindle to provide a handle 14d by which the reel is rotated.

The manner of operation of the reel should now be obvious. The reel is ordinarily carried in the folded position shown in Fig. 3 with the reel arms 12-14 nested together and clamped tightly to the spindle 10 by wing nut 21. When it is desired to erect the reel, wing nut 21 is loosened, arm 13 is rotated on the spindle 10 and placed in channel 18, and arm 14 is similarly rotated and placed in its channel 17. All of the arms would then be in the position shown in Fig. 2 and a retightening of wing nut 21 clamps the arms 13 and 14 in their respective channels 17, 18 against the shoulder portion 10c on the spindle. To wind on the line 22, spindle 10 is held loosely in one hand, the handle 14d is grasped in the other and the line 22 is wound on as shown in Fig. 1 by applying a rotary motion to the reel about the spindle axis.

When the line is dry, it may then be removed. Using the reverse procedure, the reel can then be knocked-down so that the arms 12-14 will again lie flat together as shown in Fig. 3. It is self evident from this view that the reel takes up but very little space when folded.

In Figs. 1-6, arms 13 and 14 are located in their proper spaced angular positions relative to arm 12 when the reel is erected by inserting the shank portions of these arms in the open channels in plate 11 as described. In two modified forms of the invention as shown in Figs. 7-9, different constructions are used for locating the reel arms in their spaced angular positions. Referring now to Figs. 7-8, and in particular to Fig. 7, the reel is seen to comprise of a spindle of the same construction as that shown in Figs. 1-3 and hence all parts of the spindle, and the wing nut have been designated by like reference characters.

The reel arms 23-25 which are T-shaped are stamped from sheet metal or may be made of molded plastic as distinguished from the rod construction shown in the first embodiment. These arms have holes 23a-25a at one end for assembly on the threaded portion 10a of the spindle and are turned through 90° at their other end adjacent the cross piece of the T to provide winding surfaces 23b-25b for the line to be dried. Finger portions 23c-25c on the arms are provided to prevent the line from slipping off of the reel and one of the arms such as arm 24 also includes a handle portion 26 by which the reel is rotated.

As with the previously described embodiment shown in Figs. 1-6, one of the reel arms is provided with means whereby the other two arms may be easily located in spaced angular positions relative thereto, the arms being 120° apart. Thus as is shown in Fig. 8 opposite face portions of the middle arm 24 adjacent the spindle opening 24a

are provided respectively with rounded sets of dimples 27, 28 that are adapted to receive complementary sets of bosses 29, 30 provided respectively on the face portions of the other two arms 23 and 25 that lie adjacent the middle arm. The complementary sets of dimples and bosses are so located on the arms that the latter will be spaced 120° apart when the sets are mated.

Figure 9 shows a slightly different arrangement for the complementary angular positioning means for the arms. Here the two outer arms 23' and 25' are provided with sets of bosses 29, 30' as in Fig. 8 but the middle arm 24' has two sets 31, 32 of drilled openings in lieu of the dimple sets for receiving the sets of bosses shown in Fig. 8. Otherwise the construction is the same as that shown in Figs. 7 and 8.

The alternative arm constructions shown in Figs. 8 and 9 operate in the same manner. Thus for example, when arms 23 and 25 according to the Fig. 8 construction are adjusted to positions about the spindle axis relative to arm 24 such that the complementary sets of bosses and dimples mate, the arms as shown in Fig. 7 will be 120° apart and may be secured in this position by tightening thumb nut 21 which clamps the arms against the shoulder on the spindle 10. The reel shown in Fig. 7 is used in the same manner as the one illustrated in Fig. 1.

In conclusion, I wish it to be understood that while I have described and illustrated certain preferred embodiments of the invention, various changes in the construction and arrangement of parts may be made without departing from the spirit and scope of the invention as defined in the appended claim.

I claim:

In a reel of the class described, a spindle forming a hand member, three reel arms mounted on said spindle adjacent each other and adjustable angularly about the spindle axis, a generally triangular shaped plate mounted on said spindle, one of said arms being secured to said plate at one corner portion thereof and the other two arms being adapted to be received in recesses provided at the other corner portions of said plate to thereby locate said other two arms in spaced angular positions about the spindle axis, and means clamping said arms and plate to said spindle.

JAMES C. HANCOCK.
